UNITED STATES PATENT OFFICE.

IRA E. STUMP, OF CLEVELAND, OHIO.

EGG-BEATER.

1,176,409.

Specification of Letters Patent. Patented Mar. 21, 1916.

Application filed November 15, 1915. Serial No. 61,617.

To all whom it may concern:

Be it known that I, IRA E. STUMP, a citizen of the United States, residing at Cleveland, in the county of Cuyahoga and State 5 of Ohio, have invented certain new and useful Improvements in Egg-Beaters, of which the following is a specification.

My invention relates to improvements in egg beaters, and more particularly to that 10 class or type in which stationary and rotary loops are employed, one of the loops being adapted to revolve within and in close proximity to the path of the other.

The primary object of the invention is to 15 provide a generally improved sanitary device of this class which will be exceedingly simple in construction, cheap of manufacture, and efficient in use.

A further object is the provision of an 20 improved egg beater which may be readily operated by one hand through the medium of the improved spiral actuating plunger or handle suitably arranged and connected to improved spiral actuating mechanism adapted 25 to intermittently engage and actuate the rotatably mounted loop through the medium of a suitable co-operating clutch or ratchet head, all the working parts being suitably inclosed within the stationary handle thereby 30 providing an exceedingly sanitary device of this class which may be easily washed and cleansed.

A further object is the provision of improved spiral and spiral actuated mechanism, together with improved means of 35 mounting and assembling the same.

With the above mentioned and other ends in view, the invention consists in the novel construction, arrangement, and combination 40 of parts, hereinafter described, illustrated in some of its embodiments in the accompanying drawings, and particularly pointed out in the appended claims.

Referring to the drawings, forming a part 45 of this specification, Figure 1, is a side elevation of an egg beater constructed in accordance with this invention. Fig. 2, a longitudinal central sectional view, the spring resisted spiral actuating plunger and handle being partially depressed and the longitudinally and circumferentially movable spiral being in engagement with the clutch or ratchet portion of the rotatably mounted loop head. Fig. 3, a longitudinal 50 central sectional view of the same, the plun-

ger and spiral being in their elevated positions preparatory to being initially pressed downwardly for a working impulse and preparatory to the longitudinal movement of the spiral into engagement with the clutch or ratchet portion of the rotary loop head. Fig. 4, a cross sectional view taken on line 4—4 of Fig. 2. Fig. 5, a view of the rotary spiral and guide shaft detached. Fig. 6, a view of a modified form of spiral and in 65 which the spiral is formed about a separate sleeve slidably and rotatably mounted on the shaft. Fig. 7, a cross sectional view taken on line 7—7 of Fig. 2, and showing more in detail the connection between the 70 lower end of the spiral and the clutch or ratchet head of the rotatably mounted loop. Fig. 8, a cross sectional view taken on line 8—8 of Fig. 3, and illustrating the stop member or head at the upper portion of the 75 spiral to prevent the withdrawing of the latter from the plunger when the plunger is returned to its initial position.

Similar numerals of reference designate like parts throughout all the figures of the 80 drawings.

The improved egg beater comprises a stationary loop head 1, provided with a plunger guide or stationary handle member 2, the latter, in the present instance, comprising a tubular barrel or casing 2, provided at its ends with guide or bearing heads 2^a. The guide or bearing heads 2^a, in the present instance, are provided with central bearing openings 2^b, to receive and contain a guide 85 shaft 3, the latter, in the present instance, being rotatably mounted and secured as against longitudinal movement by means of bearing heads 3^a.

The shaft 3, is provided with a rotary loop 4, adapted to rotate within the path of the stationary loop head 1, said rotary loop, in the present instance, being secured upon the shaft 3, by having its members wound about in opposite directions to form spiral convolutions 4^a, and terminating at opposite sides of the shaft 3, forming oppositely arranged clutch lugs or projections 4^b, (see Fig. 7) said spiral convolutions 4^a, and projections or lugs 4^b, forming what may be termed a clutch or ratchet head to receive and co-operate with the longitudinally and circumferentially movable spiral to be now described.

The spiral 5, is loosely mounted on the 110

shaft 3, and preferably comprises a single length of wire bent midway of its ends to form a stop projection 5^a, at its upper end and curled about in opposite directions to 5 form the oppositely extending convolutions loosely and rotatably mounted on the shaft 3, as shown most clearly in Figs. 2, 3, 5, 7 and 8, of the drawings, the ends of the wire forming clutch projections or lugs 5^b, adapted 10 to engage and coöperate with the similarly arranged oppositely extending lugs or projections 4^b, of clutch head 4^a, of the rotary loop 4, as shown most clearly in Figs. 2 and 7 of the drawings.

15 As a means of longitudinally and circumferentially moving or actuating the spiral member 5, in coöoperative relation to the clutch head of the rotary member 4, a non-rotatably mounted spring resisted plunger member 20 6, is slidably mounted in the plunger guide or handle member 2, said plunger member 6, in the present instance, being a disk-shaped plate provided with a centrally located slot 6^a, adapted to receive and traverse 25 the oppositely arranged convolutions of the spiral so that as the plunger 6 is initially depressed against the resistance of the spring 7, in the position as shown in Fig. 3 of the drawings, the spiral 5, will be initially depressed to engage with the lugs or projections 4^b, of the clutch head of the loop 4, and upon the downward working impulse given to the plunger member, in the present 30 instance, through the medium of the handle 8, the plunger 6, will rotate the spiral 5, and the connected loop 4, in an obvious manner and compress the spring 7, as indicated in Fig. 2 of the drawings. Upon the initial return of the plunger 6, by the action of the 35 spring 7, the spiral 5, will be initially elevated out of engagement with the clutch head of the rotary loop 4, (see Fig. 3) to permit the continued rotation of the rotary loop 4, (after sufficient momentum has been imparted) while the plunger is being returned 40 to its initial position as indicated in Fig. 3 of the drawings for a new working impulse.

45 The stop projection 5^a, at the top of the spiral, will prevent the plunger 6, from sliding off of the spiral when returned to its initial position as indicated in Fig. 3 of the drawings preparatory to being given a new working impulse or stroke.

50 If desired, the spiral 5, may be formed of two separate spirally arranged lengths of wire clamped about or secured upon a sleeve 9, loosely mounted on the shaft 3, the lower ends of the sleeve 9, being provided 55 with clutch projections or lugs 9^a, for use in lieu of the projections or lugs 4^b, hereinbefore referred to, and adapted to engage with the clutch projections or lugs 5^b, of the spiral in a similar manner, the upper 60 ends of the two spirally arranged members

terminating in stop projections 5^c, for use in lieu of the stop projection 5^a, of the spiral 5, hereinbefore referred to.

It will be observed that the side members of the handle 8, are slidably mounted in 70 guide openings 2^c, of the upper guide head, thereby effectively guiding the handle in its working impulses and also preventing the rotation or circumferential movement of the plunger member 6, in circumferentially moving or actuating the spiral 5.

75 From the foregoing description, taken in connection with the accompanying drawings, the operation and advantages of my invention will be readily understood. 80

Having thus described some of the embodiments of my invention, what I claim and desire to secure by Letters Patent, is,—

1. An egg beater, comprising a stationary 85 loop provided with a plunger guide handle, a rotary shaft terminating in a rotary element within said stationary loop, a spiral on said rotary shaft, a spiral actuating plunger member mounted in said plunger guide handle, and a clutch adapted to be thrown 90 into and out of engagement with said rotary shaft and element upon the initial downward and return strokes of said plunger member.

2. An egg beater, comprising a stationary 95 loop provided with a plunger guide member, a rotary shaft terminating in a rotary loop within said stationary loop, a spiral mounted on said rotary shaft, a clutch between said shaft and spiral, and a non-rotatably mounted spiral actuating member mounted in said plunger guide member in coöoperative relation to said spiral and clutch whereby said clutch is thrown into and out 100 of engagement with said spiral and shaft upon the initial downward and return strokes of said plunger to impart a continuous rotary movement to said rotary shaft and loop. 105

3. An egg beater, comprising a tubular 110 plunger guide handle provided with bearing heads having centrally located bearing openings, a stationary loop head mounted in one of said bearing heads, a rotary shaft mounted in said centrally located bearing openings 115 and provided at its lower end with a rotary element within said stationary loop head, a spiral member on said rotary shaft, a spiral actuating plunger in said plunger guide handle, a clutch adapted to move into and out of engagement with said rotary shaft upon the initial downward and return working impulses imparted to said plunger. 120

4. An egg beater, comprising a stationary 125 loop provided with a plunger guide member, a rotary shaft terminating in a rotary loop within said stationary loop, a spiral vertically and circumferentially movable on said rotary shaft, in coöoperative relation to said rotary loop and a non- 130

- rotatably mounted spring resisted spiral actuating plunger member mounted in said plunger guide member in coöperative relation to said spiral and rotatably mounted 5 loop.
5. An egg beater, comprising a stationary loop head provided with a guide member, a rotary loop head provided with a clutch, a vertically and circumferentially movable 10 spiral carried by said guide member of said stationary loop head, and a spring resisted spiral actuating plunger adapted to rotate said spiral and move the same into and out of engagement with said clutch member 15 upon the initial downward and return working impulses, respectively, of said plunger.
6. An egg beater, comprising a stationary loop and guide handle, a rotary loop provided with a clutch head within said guide 20 handle, a spiral longitudinally and circumferentially movable in said guide handle, a spring resisted spiral actuating plunger member within said guide handle, and a plunger handle operating in said guide handle and adapted to throw said spiral into and out of engagement with said rotary loop 25 upon the initial depressing and return movements of said handle and plunger member.
7. An egg beater, comprising a stationary 30 loop provided with a plunger guide member, a second loop provided with a clutch head rotatably mounted within said guide member, a spiral longitudinally and circumferentially movable in said guide member in 35 coöperative relation to said clutch head, and a spring resisted plunger and plunger handle coöperating with said spiral whereby the same is longitudinally and circumferentially moved in coöperative relation to said 40 second loop and clutch head.
8. In an egg beater, the combination with a stationary loop provided with a guide member, a rotary loop provided with a clutch head within said guide member, a 45 vertically and circumferentially movable spiral within said guide member in coöperative relation to said clutch head, a spring resisted spiral actuating plunger member in said guide member, and a handle slidably 50 mounted in said guide member and connected with said plunger whereby the latter is adapted to longitudinally and circumferentially move said spiral in coöperative relation to said clutch head.
- 55 9. In an egg beater, the combination with a stationary loop head provided with a guide handle, and a second loop provided with a clutch member rotatably mounted within said guide handle; of a longitudinally and 60 circumferentially movable spiral arranged in said guide handle in coöperative relation to said clutch, and a spring resisted plunger on said spiral and within said handle adapted to rotate said spiral and move the same 65 into and out of engagement with said clutch member upon the initial downward and return working impulses, respectively, of said plunger.
10. In an egg beater, the combination with a guide shaft provided at one end with a loop formed of a single length of wire having its ends spirally wound about said guide shaft and terminating to form oppositely disposed clutch projections; of a spiral longitudinally and circumferentially 70 movable on said shaft formed of a single length of wire bent midway of its ends forming a stop projection and having oppositely wound spiral members terminating at their lower ends in oppositely disposed clutch 75 projections adapted to engage and coöperate with said clutch projections of said rotary loop and means for operating said spiral.
11. An egg beater, comprising a stationary 80 loop head provided with a tubular guide member, a rotary head provided with a clutch member within said guide member, a vertically and circumferentially movable spiral in said tubular guide member adapted 85 to be thrown into and out of engagement with said clutch member to actuate said rotary loop head, and a non-rotatably mounted spring resisted spiral actuating plunger within said tubular guide member adapted 90 to rotate said spiral and move the same into and out of engagement with said clutch member upon the initial downward and return working impulses, respectively, of said 95 plunger.
12. In an egg beater, the combination with a stationary loop head provided with a guide, and an inner loop provided with a clutch arranged within said guide; of a longitudinally and circumferentially movable 100 spiral adapted to be thrown into and out of engagement with said clutch to rotate said second loop and provided at its top with a stop member, a plunger adapted to traverse and to longitudinally and circumferentially move said spiral, and a spring adapted to return said plunger and spiral to their initial positions after each working impulse to hold said spiral out of engagement with said clutch member until said 105 plunger is initially pressed for another or succeeding working impulse.
13. In an egg beater, a stationary loop head provided with a plunger guide handle, a guide shaft in said guide handle, a second 110 loop within said first mentioned loop head curled about said guide shaft and terminating in oppositely arranged clutch lugs, a spiral formed of a single length of wire bent upon itself and loosely wound about said shaft terminating at its lower ends in clutch 115 projections adapted to be thrown into and out of engagement with said clutch lugs of said loop, the upper end of said spiral terminating in a stop projection, and a spring 120
- 65 9. In an egg beater, the combination with a stationary loop head provided with a guide handle, a guide shaft in said guide handle, a second loop within said first mentioned loop head curled about said guide shaft and terminating in oppositely arranged clutch lugs, a spiral formed of a single length of wire bent upon itself and loosely wound about said shaft terminating at its lower ends in clutch 125 projections adapted to be thrown into and out of engagement with said clutch lugs of said loop, the upper end of said spiral terminating in a stop projection, and a spring 130

resisted spiral actuating plunger in said guide handle adapted to move said clutch lugs of said spiral into and out of engagement with said clutch projections of said 5 second loop upon the initial downward and return working movements, respectively, of said plunger.

14. An egg beater, comprising a tubular plunger guide handle provided with bearing 10 heads having centrally located bearing openings, a stationary loop head mounted in one of said bearing heads, a guide shaft mounted in said centrally located bearing openings and provided at its lower end with a rotary 15 loop provided with a clutch head, a spiral member longitudinally and circumferentially movable on said guide shaft the upper end of said spiral being provided with a stop projection and the lower end provided 20 with clutch projections adapted to coöperate with said clutch head of said rotary loop, a spring resisted spiral actuating plunger mounted in said plunger guide handle and adapted to move said spiral clutch projections 25 into and out of engagement with said clutch head upon the initial downward and return strokes of said plunger, and a double armed plunger actuating handle slidably mounted in one of said bearing heads of said 30 guide handle adapted to actuate said plunger and prevent the circumferential movement of the latter relative to said spiral.

15. An egg beater, comprising a tubular plunger guide handle provided with bearing 35 heads having centrally located bearing open-

ings, a stationary loop head carried by one of said bearing heads, a rotary shaft mounted in said centrally located bearing openings and provided with a rotary beater element within said stationary loop head, a 40 spiral on said rotary shaft, a spiral actuating plunger in said plunger guide handle, a clutch adapted to be thrown into and out of engagement with said rotary shaft upon the initial downward and return strokes of 45 said plunger, and a double-armed plunger actuating handle slidably mounted in one of said bearing heads of said guide handle adapted to actuate said plunger and prevent the circumferential movement of the latter 50 relative to said spiral.

16. An egg beater, comprising a plunger guide handle terminating in a stationary loop head, a rotary shaft mounted therein and provided with a rotary beater element 55 within said stationary loop head, a spiral member on said rotary shaft including a vertically and circumferentially movable clutch member, and a spiral actuating plunger mounted in said plunger guide handle 60 adapted to move said clutch member into and out of engagement with said rotary shaft upon the initial downward and return strokes of said plunger member.

In testimony whereof I have affixed my 65 signature in the presence of two witnesses.

IRA E. STUMP.
